ATTORNEYS

UNITED STATES PATENT OFFICE.

THOMAS McSHERRY, OF LONG BRANCH, NEW JERSEY.

TRUSS.

Application filed October 3, 1924. Serial No. 741,447.

To all whom it may concern:

Be it known that I, THOMAS McSHERRY, a citizen of the United States of America, and resident of Long Branch, in the county 5 of Monmouth and State of New Jersey, have invented a new and Improved Truss, of which the following is a full, clear, and exact description.

This invention relates to anatomical 10 trusses or supports and has particular reference to an ano-rectal truss or support which affords means for properly supporting and treating the tissues of the ano-rectal region where the same have become 15 weakened or otherwise afflicted.

One of the outstanding objects of the 20 present invention is to provide a truss or support of this character which is capable of a wide range of adjustment whereby the same may be readily regulated to register with the afflicted part and properly maintain in position against accidental displacement and this without discomfort to the wearer.

25 The invention furthermore comprehends in a truss of this type, a base which may be employed as a means for holding and positioning an obturator of an absorbent pad saturated with a suitable medicant or curative substance.

As a still further object the invention comprehends a truss or support of the character described which is comparatively simple in its construction, inexpensive to manufacture and produce and which is highly efficient in its purpose.

With the above recited and other objects in view, the invention resides in the novel construction set forth in the following specification, particularly pointed out in the appended claims and illustrated in the accompanying drawings, it being understood that the right is reserved to embodiments other than those actually illustrated herein, to the 40 full extent indicated by the general meaning of the terms in which the claims are expressed.

In the drawings—

Figure 1 is a perspective view of the 50 truss.

Fig. 2 is a plan view of the pad element parts being broken away and shown in section.

55 Fig. 3 is a side view of the pad element with parts broken away and shown in section.

Fig. 4 is a longitudinal sectional view through the pad element illustrating a piece of absorbent material and the manner in which the same is associated with the base. 60

Fig. 5 is a perspective view on a reduced scale illustrating the application of the truss.

Referring to the drawings by characters of reference the truss comprises a suitable 65 supporting belt 10 which is adapted to encircle the abdomen and is provided at its front portion with a buckle 11 for facilitating the application and removal of the belt. At the rear the belt is provided with a 70 depending looped tab 12. The pad element of the truss comprises a base 13 having its major width at the medial portion and of gradual decreasing widths toward its opposite ends. The base is provided with a pair 75 of longitudinal spaced parallel bores 14 and is formed on its upper face with an interiorly threaded recess 15. An obturator including a substantially semi-spherical body 16 and a reduced threaded shank 17 is designed for detachable association by threadedly engaging the shank within the threaded recess 15. The base 13 is further provided with a pair of apertures 18 extending through the thickness thereof at the medial 80 enlarged portion which apertures communicate with the recess whereby when it is desired to use a piece of absorbent material 19 as illustrated in Fig. 4 threads 20 may be passed through the apertures and the absorbent pad 19 to attach said absorbent pad to the base. In order to provide means for 85

connecting and supporting the pad element of the truss with the belt and to allow for proper adjustment of the pad element so that it may register with the afflicted part, a strap or tape is employed which is doubled upon itself to provide a bight portion 21 and a pair of leads 22 of substantially equal length. The bight portion 21 is engaged in the depending looped tab 12 and the leads 22 are threaded respectively through the bores 14 of the pad element base 13 which permits of relative sliding movement of the base on the leads 22. The free terminals or ends of the leads 22 are then tied around the belt at substantially diametrically opposite points. When the proper adjustment of the base 13 is obtained and the ends are tied to suit the 90

positioning of the device with respect to the individual, further adjustment is unnecessary and the removal and application of the 100

device is accomplished simply by engaging and disengaging the buckle end of the belt from the complementary end thereof.

From the foregoing it will thus be seen that a truss of the character set forth has been devised which may be manufactured and sold in one standard size and which may be initially adjusted by each individual to suit his particular case, after which no further adjustment is necessary except possibly to take up or compensate for stretching or wear on the elements.

I claim:

1. In an ano-rectal truss, a pad element comprising a base provided with a threaded socket and a plurality of apertures extending entirely through the base for receiving binding members, and an obturator formed with a rounded contact surface and a threaded portion normally screwed into said socket.

2. In an ano-rectal truss, a pad element comprising a base longer than it is wide provided with a pair of bores extending longitudinally through said base for receiving supporting straps, a threaded socket in the upper part for receiving an obturator, and a plurality of apertures for receiving binding threads for securing an obturator on the base, and an obturator formed with a reduced threaded extension normally screwed into said socket.

3. In an ano-rectal truss a pad element comprising a base and means for adjustably supporting the same from the body of the wearer, said base having a recess in its upper face for the reception of an absorbent pad, and a plurality of apertures through its thickness communicating with the recess for the reception of retaining means for holding the absorbent pad in said recess.

THOMAS McSHERRY.
